US00D867819S

(12) **United States Design Patent** (10) **Patent No.:** **US D867,819 S**
(45) **Date of Patent:** **** Nov. 26, 2019**

(54) **CRANK HANDLE**

(71) Applicant: **Ontel Products Corporation**, Fairfield, NJ (US)

(72) Inventor: **Ross Exley**, Morristown, NJ (US)

(73) Assignee: **Ontel Products Corporation**, Fairfield, NJ (US)

(**) Term: **15 Years**

(21) Appl. No.: **29/667,412**

(22) Filed: **Oct. 22, 2018**

Related U.S. Application Data

(62) Division of application No. 15/053,857, filed on Feb. 25, 2016.

(51) **LOC (12) Cl.** **31-00**

(52) **U.S. Cl.** **D7/412; D7/381**
USPC **D7/412; D7/381**

(57) **CLAIM**

The ornamental design for a crank handle, substantially as shown as described.

DESCRIPTION

FIG. 1 is a front elevated isometric view of my design;

FIG. 2 is a rear bottom isometric view of my design;

FIG. 3 is a front side view of my design;

FIG. 4 is a rear side view of my design;

FIG. 5 is a right side view of my design;

FIG. 6 is a left side view of my design;

FIG. 7 is a top view of my design; and,

FIG. 8 is a bottom view of my design.

The broken lines shown in the drawings are included for the purpose of illustrating an environmental structure and form no part of the claimed design.

1 Claim, 6 Drawing Sheets
